UNITED STATES PATENT OFFICE.

OTTO THIEME, OF HARTFORD, CONNECTICUT, ASSIGNOR, BY MESNE ASSIGNMENTS,
TO UNDERWOOD COMPUTING MACHINE COMPANY, OF NEW YORK, N. Y., A COR-
PORATION OF NEW YORK.

TYPEWRITING MACHINE.

Application filed September 5, 1922. Serial No. 586,074.

To all whom it may concern:

Be it known that I, OTTO THIEME, a citizen of the United States, residing in Hartford, in the county of Hartford and State of Connecticut, have invented certain new and useful Improvements in Typewriting Machines, of which the following is a specification.

The present invention relates to typewriting machines. More particularly, the invention, as to one feature thereof, relates to tables used in connection with so-called continuous billing typewriting machines. As to other features thereof, the invention relates to column-stop bars and column-stops.

In continuous billing typewriting machines, work-sheets or webs are used in several layers or plies, each provided with printed forms constituting one piece of work, which, when completed, may be torn from the continuous web. Carbon-sheets interleaved between the webs or plies are mounted on a carbon-carriage, so as to advance with the web toward the platen while typewriting, and so as to be drawn back by the carbon-carriage into the succeeding form-section of the web after the leading form-section has been typed, and prior to detachment from the web of such leading form-section. Such a carbon-carriage is ordinarily mounted for movement on a table connected to the platen carriage at the rear of the machine. When set for typewriting, this table commonly interferes with easy access to the column-stops and other devices and parts at the rear of the machine, which from time to time require adjustment or other attention. Consequently, resort has heretofore been had to various means for moving the table to provide clearance to the rear of the machine when desired.

An object of the invention is the provision of means whereby, without actually detaching the table from the machine, and without involving the introduction of guards at the pivots of the table to hold the table on its support, the table by a simple and easy movement may be swung on its pivots between its normal or typewriting position and a position in which the column-stops and other parts at the rear of the machine are conveniently accessible. Features of the invention are the provision on the platen carriage of fixed devices or guideways in

which the forward end of the table moves when swung on its support between the positions mentioned; and the provision of durable and simple means for effectively and automatically locking the table in either position.

A further object of the invention is the provision of means for adjusting, setting and holding the column-stop bar or rack in such position that the stops, when set thereon at indicated column positions, will be accurately set.

Another feature of the invention is a column-stop which may be placed and replaced on the stop-bar with minimum trouble; and which, although of cheap and simple construction, is of great strength and rigidity, in its interlockment with the stop-bar, to withstand the impacts of the carriage in the jumps of the latter from one to another column position.

Other features and advantages will hereinafter appear.

In the accompanying drawings,

Figure 1 is a view, in side elevation, of a typewriting machine and attached carbon-carrier table, embodying the several features of the present invention.

Figure 2 is a detail view, in side elevation, of the connections of the carbon-carrier table to the typewriting machine.

Figure 3 is a top plan view of the carriage of the typewriting machine and connections of the carbon-carrier table thereto.

Figure 4 is a front view, partly broken, showing the right-hand connections of the carbon-carrier table to the carriage of the typewriting machine, and showing the adjustable attachment of the stop and scale bar to the carriage.

Figure 5 is a detail view, in top plan, partly broken, of the mechanism shown in Figure 4.

Figure 6 is a rear view, both right and left hand side, of the mechanism, the right-hand side of which is shown at Figure 4.

Figure 7 is a perspective view of one of the stops.

Referring to the drawings, the platen 16 is carried by an axle 11 journaled in arms 12 forming part of a frame pivoted on a shaft 13, which connects and is carried by side plates 14 of the carriage. The normal or printing position of the platen and of the

frame pivoted on the shaft 13 is that shown in Figure 1. These parts may be swung up around the shaft 13, to permit fan-fold or manifold webs to be advanced in a well-known manner, for detachment of the leading or written section thereof and for placement of the succeeding section. The line-space movement of the platen, by means of handwheels 15 and by means of a line-space lever 16, may be effected, both when the platen is in its normal position and when it has been swung up for a gross movement of the web.

For this purpose, there is a gear 17 attached to each end of the platen-axle 11, each gear 17 being in mesh with one of two gears 18 journaled on the shaft 13, and each gear 18 being in mesh with one of two gears 19 fastened on stub shafts 20 journaled in the side plates of the carriage. Each shaft 20 has fastened thereto one of the hand-wheels 15. The left-hand shaft 20 also has fast thereto a ratchet-wheel (not shown), forming part of a line-spacing mechanism operable by the line-space lever 16. This line-spacing mechanism is not fully shown in the drawings, but is of the construction found in Underwood typewriting machines.

30 Line-space movement of the shaft 20, whether by the wheel 15 or by the line-spacing mechanism, causes the gear 19 to turn the gear 18, and, through the latter, to turn the gear 17 and with it the platen. When 35 the platen is swung up around the shaft 13, the gears 17 remain in mesh with the gears 18, and consequently the line-space movement of the platen may be effected, as when the parts are in the printing position.

40 The swinging frame is shown as having a paper-shelf 21 secured to a cross-bar 22 thereon, and as having side plates or arms 23 provided with pins 24 adapted to be engaged by hooks 25 fast to a rock-shaft 26 45 journaled in side members 27 of the carriage. A spring 28 causes the hooks 25 to be thrust forward to engage the pins 24 on the swinging frame, thereby locking the latter and the platen down in normal or 50 printing position. In moving the platen to normal position, the pins 24 force back the hooks 25 until the latter are free to swing over the pins. For releasing the hooks to permit the platen to be swung up, the left- 55 hand hook is shown as extended at 29 to carry a finger-piece 30 by means of which the hooks and rock-shaft 26 may be swung backward until the hooks are clear of the pins 24.

60 The carriage is shown as provided with the usual paper-guide and apron 31 carried by a cross-piece 32, which connects the side plates of the carriage. The carriage has movement in letter-feed and return directions on a rod 33 on the main frame 34 of

the typewriting machine. The parts thus far described are not new with the present invention.

As heretofore mentioned, the typewriting machine of the present invention has attached thereto a carbon-carrier table over which a manifold or fan-fold web may be fed to the platen, and on which a carbon-carrier has line-space movement forward with a web and movement backward relative to the web to shift carbons from one web-section to another. This table is shown at 75 35 supported on a standard 36 secured to the main frame of the typewriting machine at the rear of the latter. The carbon-carrier is indicated at 37 on the table 35. It is unnecessary to describe in detail the construction of the carbon-carrier and the mounting thereof on the table, reference being made to United States Letters Patent to B. P. Fortin, No. 1,237,319, of August 21, 1917, for such description thereof as may be desired. Suffice here to say that the carbon-carrier or holder of the Fortin patent 80 comprises a plate 38 having secured thereto 85 clips (not shown), each of which clips engages and holds the rear end of a carbon-sheet; the several clips being stepped up, one from another, on steps 39, more conveniently to enter and slide between the superposed 90 web plies.

Since the table 35 is to have movement in letter-feed and return directions with the typewriter carriage, it is provided with rollers 40 carried by brackets 41, which ride on a rail 42 fast to the standard 36 at the rear thereof. At its forward end, the table 35 is connected to brackets 43 and 44 on the typewriter carriage. As shown in Figure 2, with reference to the bracket 43, these 100 brackets are secured by screws 45 to the cross-bar 32 of the carriage. The bar 46, which forms the forward cross-reach of the table 35, has a stud 47 threaded into each end thereof, and the studs 47 pass through arcuate slots 48 in upwardly-projecting arms 49, one on each of the brackets 43 and 44. The normal position of the table 35 is the full line, Figure 1, position thereof, in 105 which position the studs 47 are at the lower ends of the slots 48. For locking the table in this position, there is a sleeve 50 movable longitudinally on each of the studs 47 into and out of a circular enlargement 51 of each of the slots 48 at the lower ends thereof. The table 35 is pivotally mounted to swing 110 on the rail 42, but when, as shown in Figure 5, the sleeves 50 on the studs 47 are in the enlargements 51 of the slots 48, the studs 47 and consequently the table 35 are held 115 against upward movement.

In order that the table may not become accidentally unlocked, and in order that it may be automatically locked when swung to correct position, the sleeves 50 are enlarged 120

beyond the arms 49 of the brackets 43 and 44 to provide chambers which receive the heads 52 of the studs 47 and which hold coil springs 53 bearing at one end against the heads 52 of the studs, and at the other end each against a shoulder 54 on the sleeve. The springs 53 cause the sleeves to press against the arms 49 and to enter the recesses at the ends of the slots therein when in registration with such recesses. Consequently, when the table 35 is swung from dotted line, Figure 1, position to full line, Figure 1, position, it is automatically locked in the latter position. When the table is to be moved to the dotted line, Figure 1, position for access to the stops or other mechanism at the rear of the typewriting machine, the sleeves 50 are seized by their knurled heads 55 and thrown laterally outward against the action of the springs 53; whereupon the table may be swung up.

For locking the table in its dotted line, Figure 1, position, one or both of the slots 48 of the arms 49 may have at the upper end a circular enlargement 56, similar to the enlargement 51 at the lower end thereof, to receive the corresponding sleeve 50; which latter, under the action of its spring 53, will enter such enlargement 56, and thereby hold the table against unintended downward movement by gravity or otherwise. It will be noted that the mounting of the table on its pivot-rod or rail 42 is such that it may swing freely thereon, and will remain connected thereto without other guards or holding devices than its connections to the brackets 43 and 44.

Nuts 57 on the studs 47, between the ends of the bar 46 and the bracket arm 49, may be turned up against the bar 46 to serve as lock-nuts for the studs. On loosening the lock-nuts 57, the studs may be turned to adjust the tension of the springs 53.

The brackets 43 and 44, which serve as connections for the table 35, also serve to hold the column-stop bar. This bar is in the form of a rack 58, the teeth of which are on the under side thereof. The upper face 59 of the bar is graduated at letter-space distances, numbered to correspond to the graduations and numbering on the usual letter-space scale 60 on the front cross-piece of the main frame of the machine. For accurate positioning of the rack teeth and scale of the stop-bar to bring the scale 59 into exact accord with the scale 60, in assembling the machine, and occasionally for readjustment, it is desirable that the bar 58 be adjustable lengthwise of the platen. Such adjustment is provided for as follows. The horizontal arms 61 of the brackets 43 and 44 have blocks 62 secured to the upper faces thereof by pins 63. The under side of the stop-bar 58 is cut away, as at 62^a, beyond the rack to receive the blocks 62. These blocks are

slotted at 64 lengthwise of the bar 58. Below the blocks 62, the horizontal arms 61 of the brackets 43 and 44 have holes 65 therethrough to receive heads 66 of screws 67, which pass through the slots 64 in the blocks 62 and through the bar 58, and which are held in place by nuts 69 on the top of the stop-bar 58. The heads 66 of the screws 67 bear against the under faces of the blocks 62, and when the nuts 69 are tightened the bar is held against movement. The holes 65 in the arms 61 of the brackets are of such size that when the nuts 69 are loosened the screws 67 may have movement with the bar lengthwise of the slots 64 in the blocks 62. This movement is effected and controlled by a turn-screw 70, which is threaded into the righthand end of the stop-bar, and which has a head 71 adapted to bear against a finger or offset 72 on a third arm 73 of the bracket 43. The head of the screw 70 has holes 74 therein to receive a pin for turning the screw. When the head of the screw is bearing upon the offset 72, movement of the screw in one direction will effect a delicately controlled movement of the bar to the left; provided the screws 67 have been loosened. Turning the screw 70 in the other direction, while pressing the bar to the right, results in a delicately controlled movement of the bar in that direction.

By placing one of the column-stops on the bar 58, throwing the carriage to the same, and reading the position of the carriage from the scale 60 on the main frame of the machine, the accuracy of setting of the bar 58 may be determined. When accurately set, the bar is locked by the screws 67 with the head 71 of the screws 70 against the offset 72 of the bracket 43. If the screws 67 become loosened and the bar 58 accidentally disturbed, readjustment of the same in the manner just indicated may be readily effected.

One of the column-stops is shown in Figure 7. This stop is shown as a block 75 grooved or channeled to present a plurality of teeth 76, three such teeth being shown, and each tooth being adapted to enter and fit between two adjacent teeth of the rack 58. A sheet-metal finger 77 has ears 78, by means of which it is pivoted at 79 to the block 75. A coil spring 80, seated in a pocket in the block 75, bears upward against the rear end of the finger 77 to force down the front end of that finger. The stop is forced onto the stop-bar from the rear of the latter; the teeth 76 of the stop engaging the teeth of the rack, and the finger 77 swinging up against the action of the spring 80, to pass over the top of the stop-bar.

In order that the finger 77 may be cammed up in the operation of placing the stop, the forward end of the finger is inclined upward and forward, as at 81, and preferably

the forward end of the teeth 76 are tapered down, as at 82. The inclined lip 81 at the forward end of the finger 77 forms part of a V-shaped detent 83, which snags over the 5 forward edge of the stop-bar to hold the stop to the latter after the stop has been thrust into home position. Another detent 84 of the finger 77 serves as a tooth or bearing for the latter on the top of the bar, and as a 10 stop to determine the throw of the finger under the action of the spring 80. In order that the stop may find its position in the rack without trouble to the operator, the upper edges of the inclined portion 82 of the 15 teeth 76 are preferably tapered off, as indicated at 85. To prevent overthrow of the finger 77 and possible displacement of the spring 80 when the stop is not in use, there is a tooth 86 formed on one of the ears 78 of 20 the finger 77 for engagement with a pin 87 on one side of the block 75.

For co-operation with the denominational-stops, the block is provided with an elongated tooth or lip 88 which depends from 25 the lower face thereof into the field of action of the denominational-stops. After the tooth 88 has been stepped beyond the denominational-stop, the latter may be lifted up behind the tooth 88, and under the 30 block 75, preliminary to a jump of the carriage to the next column-stop. The tooth 88 is tapered at its edge, so that the denominational-stop may not be blocked thereby on being lifted. The denominational-stop 35 mechanism may be that found on the standard Underwood typewriting machine, and so is not here shown or described.

Variations may be resorted to within the 40 scope of the invention, and portions of the improvements may be used without others.

Having thus described my invention, I claim:

1. The combination with a typewriting machine having a platen, of a table at the 45 rear of the machine over which a continuous work-sheet may be fed to the platen, a standard on which the table is pivotally mounted to permit the forward end thereof to be swung up and down, and a guide-way on the machine in which the forward end of the table is held when the table is swung on its pivot.

2. The combination with a typewriting machine having a platen, of a table at the 55 rear of the machine over which a continuous work-sheet may be fed to the platen, a standard on which the table is pivotally mounted to permit the forward end thereof to be swung up and down, a finger on the forward end of the table, and a bracket on the machine having an arcuate guide-way thereon in engagement with a finger on the table to hold the table to the machine when the table is swung on its pivot.

3. The combination with a typewriting

machine having a platen, of a table at the rear of the machine over which a continuous work-sheet may be fed to the platen, a standard on which the table is pivotally mounted to permit the forward end thereof to be swung up and down, a stud on the forward end of the table, a bracket on the machine having an arcuate slot therein for the stud, and a sleeve or collar on the stud 70 slidable longitudinally thereof and adapted to enter an enlargement at the end of the slot to lock the table in normal position.

4. The combination with a typewriting machine having a platen, of a table at the rear of the machine over which a continuous work-sheet may be fed to the platen, a standard on which the table is pivotally mounted to permit the forward end thereof to be swung up and down, a stud on the forward end of the table, a bracket on the machine having an arcuate slot therein for the stud, and a sleeve or collar on the stud 80 slidable longitudinally thereof and adapted to enter enlargements, one at each end of the slot, to lock the table in its normal position or in a position to which it may be thrown for access to parts of the rear of the machine.

5. The combination with a typewriting machine having a platen, of a table at the rear of the machine over which a continuous work-sheet may be fed to the platen, a standard on which the table is pivotally mounted to permit the forward end thereof to be swung up and down, a stud on the forward end of the table, a bracket on the machine having an arcuate slot therein for the stud, a sleeve or collar on the stud 90 slidable longitudinally thereof and adapted to enter an enlargement at the end of the slot to lock the table in normal position, and a spring for effecting and maintaining a table-locking position of the sleeve or collar.

6. The combination with a typewriting machine having a platen, of a table at the rear of the machine over which a continuous work-sheet may be fed to the platen, a standard on which the table is pivotally mounted to permit the forward end thereof to be swung up and down, a stud on the forward end of the table, a bracket on the machine having an arcuate slot therein for the stud, a sleeve or collar on the stud 100 slidable longitudinally thereof and adapted to enter an enlargement at the end of the slot to lock the table in normal position, and a coil spring held between the head of the stud and a shoulder on the sleeve for effecting and maintaining a table-locking position of the sleeve or collar.

7. The combination with a typewriting machine having a platen, of a table at the rear 110 of the machine over which a continuous

work-sheet may be fed to the platen, a standard on which the table is pivotally mounted to permit the forward end thereof to be swung up and down, a stud on the forward end of the table, a bracket on the machine having an arcuate slot therein for the stud, a sleeve or collar on the stud slideable longitudinally thereof and adapted to enter an enlargement at the end of the slot to lock the table in normal position, and a coil spring held between the head of the stud and a shoulder on the sleeve for effecting and maintaining a table-locking position of the sleeve or collar, said stud being adjustable to vary the tension of the spring.

8. The combination with a typewriting machine having a rotary platen and a carriage for effecting letter-feed and return movements of the platen, of a table at the rear of the machine over which continuous work-sheets may be fed to the platen, a standard having a rail on which the table is movable with the carriage and on which the table is pivotally mounted to be swung up and down, studs on the forward end of the table, and brackets on the carriage having guideways in which the studs are set to hold the table to the carriage and to permit movement of the table on its pivot.

30 9. The combination with a typewriting machine having a rotary platen and a carriage for effecting letter-feed and return movements of the platen, of a table at the rear of the machine over which continuous work-sheets may be fed to the platen, a standard having a rail on which the table is movable with the carriage and on which the table is pivotally mounted to be swung up and down, studs on the forward end of the table, brackets on the carriage having guideways in which the studs are set to hold the table to the carriage and to permit movement of the table on its pivot, and means for locking the table to the brackets in the normal position of the table.

10. The combination with a typewriting machine having a rotary platen and a carriage for effecting letter-feed and return movements of the platen, of a table at the rear of the machine over which continuous work-sheets may be fed to the platen, a standard having a rail on which the table is movable with the carriage and on which the table is pivotally mounted to be swung up and down, studs on the forward end of the table, brackets on the carriage having guideways in which the studs are set to hold the table to the carriage and to permit movement of the table on its pivot, and means for locking the table to the brackets in the normal position of the table, and for locking the table to the brackets in the position to which the table has been swung

on its pivot for access to parts of the rear of the machine.

11. The combination with a typewriting machine having a rotary platen and a carriage for effecting letter-feed and return movements of the platen, of a table at the rear of the machine over which continuous work-sheets may be fed to the platen, a standard having a rail on which the table is movable with the carriage and on which the table is pivotally mounted to be swung up and down, studs on the forward end of the table, and brackets on the carriage having upright arms with arcuate slots therein to receive the studs for holding the table to the carriage while permitting the same to be swung on its pivot.

12. The combination with a typewriting machine having a rotary platen and a carriage for effecting letter-feed and return movements of the platen, of a column-stop bar on the rear of the machine, column-stops on the stop-bar, a table at the rear of the machine over which continuous work-sheets may be fed to the platen, a standard having a rail on which the table is movable with the carriage and on which the table is pivotally mounted to be swung from a normal position to a position to permit of access to the stops, studs on the forward end of the table, and brackets on the carriage having guideways in which the studs are set to hold the table to the carriage and to permit movement of the table on its pivot between its normal or printing position and the position thereof permitting access to the stops.

13. The combination with a typewriting machine having a platen, of a table at the rear of the machine over which a continuous work-sheet may be fed to the platen, a standard on which the table is pivotally mounted to permit the forward end thereof to be swung up and down, and means on the machine for holding the table thereto when the table is swung on its pivot.

14. The combination with a typewriting machine having a rotary platen and a carriage for effecting letter-feed and return movements of the platen, of a table at the rear of the machine over which continuous work-sheets may be fed to the platen, a standard having a rail on which the table is movable with the carriage and on which the table is pivotally mounted to be swung up and down, and means on the platen carriage for holding the table on the rail when it is swung on the latter as a pivot.

OTTO THIEME.
